MULTIPLE TOOL

Filed Dec. 26, 1922

INVENTOR,
Joseph J. Judge
BY
S. J. Church
his ATTORNEY

UNITED STATES PATENT OFFICE.

JOSEPH J. JUDGE, OF ROCHESTER, NEW YORK.

MULTIPLE TOOL.

Application filed December 26, 1922. Serial No. 608,815.

This invention relates to combination or multiple tool sets and more particularly to the variety comprising a plurality of operating parts such, for example, as a series of wrench sockets of various sizes, assembled upon the tool itself. One object of the invention is to provide an efficient tool of the above character adapted for accomplishing work rapidly under various conditions of use as, for example, in a confined space and without requiring removal from the nut or other object upon which work is being done. Another object is the provision of such a tool adapted to include a relatively large number of working parts and so constructed as to facilitate the assembly and removal of the latter as required in use. Still a further object is to provide a tool of this character having a thoroughly practical form of construction capable of being produced at a relatively low cost. To these and other ends the invention resides in certain improvements and combinations of parts all as will be hereinafter more fully described, the novel features being pointed out in the claims at the end of the specification.

In the drawings:

Fig. 1 is a side view of a multiple tool embodying the present invention and showing the various working parts compactly assembled thereon;

Figs. 2 and 3 are fragmentary detail views showing different working parts associated with the tool as in use;

Fig. 4 is a sectional view on the line 4-4 in Fig. 1;

Fig. 5 is a sectional view on the line 5-5 in Fig. 6;

Fig. 6 is an enlarged sectional view illustrating the connection of a wrench socket with the tool by a universal joint;

Fig. 7 is a fragmentary perspective view illustrating the use of the tool as a lever, as for lifting motor valves;

Fig. 8 is a central sectional view of a handle portion of the tool; and

Fig. 9 is a perspective view of a different form of wrench which may be used with the tool parts.

Similar reference numerals throughout the several views indicate the same parts.

The embodiment of the invention at present preferred comprises a main tool portion 10 in the form of a brace constructed of an integral metal rod having an elongated shank portion 11 and at its opposite end a

handle or breast piece 12, with an intermediate angular crank portion 13. The rod has in the present instance, a uniformly round cross-section except at the shank portion 11, the lower or key end and preferably the entire extent of which has a cross-section of uniform polygonal or hexagonal shape. The shank portion is thus adapted to slidably receive a plurality of hollow wrench sockets 14 for nuts of different sizes. The sockets have an opening formed therethrough as indicated, one end of which is hexagonal in shape and of different sizes in the different sockets to cooperate with various sized nuts. The other end of the opening through the sockets is adapted to slidably receive the brace shank so that the series of sockets may be collectively assembled or strung on the shank as shown in Fig. 1. The uniform size and shape of the shank throughout facilitates the assembly and removal of the sockets which do not require to be rotatably adjusted or otherwise positioned before being slid off the shank. The relatively close fit between the sockets and shank furthermore prevents the sockets from rattling about on the shank.

Means are provided for retaining the sockets in assembled relation on the shank when not in use comprising a cotter-pin 15, Fig. 2, inserted in a transverse opening adjacent the end of the shank. By removing this pin a socket of desired size may be taken from the shank and fitted to the key end of the latter for use as shown in Fig. 2. Pin 15 serves also as a stop for the sockets in use. To retain a socket in such operating position on the shank end the latter has a recess 16 formed therein adjacent its extremity in which is carried a ball 17 pressed outwardly by a spring 18 so as to project slightly beyond the surface of the shank for frictionally engaging and retaining a socket thereon. The end walls of opening 16 are set slightly inwardly after the insertion of the ball to limit its outward movement.

In Fig. 6 is shown an adapter comprising a socket 19 constructed for engagement with the shank end or key as in the case of the sockets 14 and carrying in its other end a transverse pin 20 on which is mounted for universal movement in any suitable manner the spherical end 21 of an auxiliary shank end or key 22 adapted for engagement with the series of sockets 14 to afford a universal form of connection between the latter and

the tool when the work requires operation of the latter at an angle. This feature and also the length of the shank portion 11 render the tool capable of use for conveniently engaging and rotating a nut located in an inaccessible position or at an inconvenient angle to the axis of the tool.

The tool embodies an advantageous form of construction for the handle or breast piece 12 in which the rod 10, Fig. 8, has a reduced portion 23 at its extremity providing a stop shoulder 24 preferably of substantial height. A collar 25 is assembled on portion 23 with an end flange 26 bearing against shoulder 24, the collar and flange being as shown of substantial thickness and strength. Handle 12 is formed with a central opening through which collar 25 is rotatably inserted with the handle supported by flange 26. A spring washer 27 is then preferably placed on collar 25 and the latter upset or rolled over at its end as at 28 to secure the handle on the collar. These latter parts may be thus assembled as a unit and then placed on the rod end 23 and the latter upset or rolled over as at 29 to hold the parts in place. This affords a substantial form of support for the handle which may of course be varied in its details although the form described has been found practical and inexpensive. In addition to the series of sockets already described the tool comprises an element 30 in the form of a sheet-metal clip, Fig. 4, folded upon itself as at 31 with spaced arms 32 embracing the shank end or key and perforated to pivotally receive the pin 15. The outer folded end 31 of the clip is shaped for engagement with one or more recessed portions of an object to be rotated as for example the valve of an internal-combustion motor for rotating and grinding the latter. Element 30 is pivotally supported on the shank by the means described which assists in operating it at inconvenient angles and also provides for compact positioning on the shank when not in use as shown in Fig. 1. Element 30 may of course be adapted for turning screws and various other objects.

The tool comprises also operating parts for lifting an object as for example, a motor valve and valve stem for grinding and other operations on the latter. The parts comprise an element 33, Fig. 7, having a socket portion 34 adapted to be fitted to the shank end or key and a bifurcated end 35 formed to embrace and engage a valve stem part for lifting the latter. To provide a means of suspension or fulcrum for the tool during such use there is supplied also an element or link 36 formed with openings 37 and 38 at its two ends preferably lying in a common plane as shown. Opening 37 adapts the element for assembly on the brace rod as shown, this opening being preferably such as to

prevent accidental detachment from the tool. The other opening 38 is such as to form a hook for engagement, for example, with the studs for holding the engine manifold on the cylinder block. These parts together with the elongated shank of the tool, provide a convenient implement or lever for lifting the valves of a motor for the purposes described.

At 39, Fig. 9, is an L-shaped wrench of a well-known form which may be supplied with the tool for use with the working parts thereof under particular conditions. This wrench is provided with a frictional device or spring-actuated ball 40 similar to that previously described, for retaining the working parts in operating position on the wrench. The material of the latter, furthermore, is pressed up as at 41 to form a lug serving as a stop for socket parts.

The operation of the tool has been described in connection with the description of its construction and it is apparent that the tool provides a relatively large number of working parts particularly useful in connection with an internal-combustion motor. These parts are associated with the tool in a convenient manner facilitating assembly and detachment as well as efficient use thereon individually, and the construction is substantial and rugged but simple and inexpensive throughout.

I claim as my invention:

1. A multiple wrench comprising a brace having an elongated shank rod provided at its end with means for engaging and rotating a wrench socket and arranged to receive a plurality of wrench sockets having openings therethrough and adapted to be strung together on said shank rod when not in use and to be associated individually and interchangeably with said socket engaging means in use and a detachable retaining device for the unused sockets forming a stop for the socket mounted in operating position upon the shank.

2. A multiple wrench comprising an elongated shank rod U-shaped at one end to provide a terminal handle concentric with the shank rod and an intermediate crank handle for rotating the same, said shank rod being provided at its other end with means for engaging and rotating a wrench socket and arranged to receive a plurality of wrench sockets for nuts of different sizes adapted to slidably embrace and be collected on said shank rod when not in use and to be associated individually and interchangeably with said socket engaging means in use and a member detachably connected with the shank rod for preventing outward movement of the unused sockets and inward movement of the socket mounted in operating position upon the shank.

3. A multiple wrench comprising a brace

- having an elongated shank rod provided with an end of polygonal cross-section for engaging in and rotating a wrench socket and arranged to receive a plurality of hollow wrench sockets for nuts of different sizes adapted to be collectively strung on said shank rod when not in use and to be individually and interchangeably fitted on said socket engaging end means for maintaining a socket in operating position on said shank rod end, and a detachable device forming an abutment for the last-mentioned socket and serving to retain the unused sockets upon the shank rod.
- 5 4. A multiple wrench comprising a brace having an elongated shank rod of polygonal cross-section throughout adapted to receive a plurality of wrench sockets having openings therethrough formed at one end for receiving nuts of different sizes and being adapted at the other to slidably fit said polygonal shank rod, said sockets being adapted to be collectively strung on said rod when not
- 10 in use and to be individually and interchangeably fitted in operating position on the end of said rod, and a pin removably interposed between the unused sockets and the one adapted for use whereby to prevent outward movement of the one and inward movement of the others.
- 15 5. A multiple wrench comprising a brace having an elongated shank rod provided at its end with means for engaging and rotating a wrench socket and arranged to receive a plurality of wrench sockets having openings therethrough permitting the sockets to be strung together on said rod when not in use and to be associated individually and interchangeably with said socket engaging means, a device for retaining unused sockets 35 in position on said rod, and frictional means for retaining a socket in association with said socket engaging means and in abutting relation with said retaining device.
- 20

JOSEPH J. JUDGE.
